UNITED STATES PATENT OFFICE.

HOMER M. HAVENS, OF COLUMBUS, OHIO, ASSIGNOR TO THE SEAGRAVE COMPANY, OF COLUMBUS, OHIO, A CORPORATION OF OHIO.

MEANS FOR PRIMING PUMPS.

Application filed February 16, 1923. Serial No. 619,349.

To all whom it may concern:

Be it known that I, HOMER M. HAVENS, a citizen of the United States, residing at Columbus, in the county of Franklin and State of Ohio, have invented a certain new and useful Improvement in Means for Priming Pumps, of which following is a specification.

This invention relates to pump priming means in which the priming pump is normally in priming connection with the main pump and is driven by the same power that drives the main pump and also has means for connecting the driving power with the priming pump shaft when the main pump is to be primed and disconnecting the power from the priming pump shaft when the priming of the main pump has been effected. The object of the present invention is to provide improved means whereby the driving power may be manually connected with the priming pump and means whereby such power is automatically disconnected from the priming pump when the main pump has been primed.

The invention is embodied in the example herein shown and described, the features of novelty being finally claimed.

In the accompanying drawing—

Figure 1 is largely a view in side elevation with such parts in section as will illustrate details of the present invention.

Fig. 2 is a detail looking toward the left of Fig. 1 at the clutch operating lever.

In the views 5 designates the main pump which is of any usual impeller type employed in fire extinguishing engines. The main pump, as shown, has a suction and a discharge opening located as indicated by the words in Fig. 1. The pump impeller shaft is designated 6 and said shaft is provided with a pinion 7 engaged by a spur gear 8 on a sleeve 9 adapted to be connected with a power shaft 10 by means of a clutch 11. The pinion 7 has its right hand face provided with a jaw clutch member 7^a.

The priming pump is shown at 12, it being communicatively connected with the main pump by means of a pipe 13 and a casing 13^a mounted on and communicating with the shell of the main pump.

The shaft 14 of the priming pump is perforated longitudinally and through said perforation is extended a rod 15 having connected to its inner or left hand end by means

of pin 16 a jaw clutch member 17 to cooperate with the clutch member 7^a. The clutch member 17 has a splined sliding connection with the inner end of the priming pump shaft 14 so that when the clutch member 17 is turned by the clutch member 7^a the shaft of the priming pump is rotated. At its outer end the rod 15 is swivelly connected with a hand lever 19 fulcrumed at 20, said lever being adapted to be operated by pressure in the main pump to release the clutch as hereinafter described.

The casing 13^a is equipped with a flexible diaphragm 21 held down by a spring 22 on a pin 23 provided with a cup shaped end 24, said pin projecting upward through the casing 13^a. Fulcrumed by means of a shaft 25 on a bracket 26 on top of the casing 13^a is a lever 27 connected at one end to the upper end of the pin 23 and connected at its other end to the stem 28 of a valve 29 arranged within the casing 13^a and adapted to open and close the pipe 13. The shaft 25 of the lever 27 has affixed to one end thereof a crank arm 30 and to the free end of the latter is hinged a rod 31 extended through an eye 32 in the hand lever 19. The free end of the rod 31 is threaded to receive a nut 33 which is adapted to be adjusted and fixed by a jam nut 34, said nut 33 constituting a lug adapted to draw on the hand lever to disconnect the priming pump operating clutch when the main pump has been primed. The character 35 designates a screen to prevent sand, sticks and other objectionable solids from passing from the main pump into the priming pump.

The operation is this: Assuming the power shaft 10 is being driven and the clutch 11 engaged therewith the handle end of the hand lever 19 is drawn outward by the attendant against the nut and to engage the clutch members 7^a and 17 thus causing the operation of the priming pump and thereby vacuumizing the chamber of the main pump the latter becoming filled with water. When the main pump is thus filled or primed the pressure, therein moves the flexible diaphragm 21 thereby lifting the left hand end of the lever 27 and simultaneously closing the valve 29 and drawing the rod 31 leftward to disengage the clutch members 7^a and 17. When the pumping operation of the main pump is stopped the spring 22 opens the valve 29 and moves the rod and

the hand lever 31 to the position shown in broken lines in Fig. 1 thereby leaving the hand lever 19 free and in position for manually reengaging said clutch members 7^a and 17 as first described.

The forms of the parts can be changed without departing from the gist of the invention as claimed.

What I claim is—

- 10 1. In combination, a main pump and its shaft, a priming pump therefor having a priming connection therewith and having a shaft, means for driving the impeller shaft of the main pump, a clutch means for operably connecting the shaft of the main pump with the priming pump shaft, manually operable means for engaging said clutch means to connect the main pump shaft with the priming pump shaft for priming the main pump, and automatically operable means for disengaging said clutch means when the main pump is primed.
- 20 2. In combination, a main pump and its shaft, a priming pump therefor having a priming connection therewith and having a shaft, means for driving the shaft of the main pump, a clutch means for operably connecting the shaft of the main pump with the priming pump shaft, manually operable means for engaging said clutch means to connect the main pump shaft with the priming pump shaft for priming the main pump, and automatically operable means for disengaging said clutch means when the main pump is primed. consisting of means actuated by pressure of the main pump when primed.

3. In combination, a main pump and its shaft, a priming pump therefor having a priming connection therewith and having a shaft, a valve in said priming connection, a clutch means for connecting the shaft of the main pump with the priming pump shaft, manually operable means for engaging said clutch means to operably connect the main pump shaft with the priming pump shaft for priming the main pump, and automatically operable means for disengaging said clutch means when the main pump is primed consisting of means actuated by pressure of the main pump when primed, and means connected therewith for actuating the manually operable means, said pressure actuated means also connected with said valve and adapted to close said valve.

4. In combination, a main pump and its shaft, a priming pump therefor having a priming connection therewith and also having a shaft, a valve in said priming connection, a clutch means for connecting the shaft of the main pump with the priming pump shaft, manually operable means for engaging said clutch means to operably connect the main pump shaft with the priming pump shaft, an automatically operable means for disengaging said clutch means when the main pump is primed consisting of a rod provided with a lug to operate on said manually operable means to disengage said clutch and means actuated by means of pressure in the main pump when primed to so actuate said rod and close said valve.

HOMER M. HAVENS.
